STARTER DRIVE FOR INTERNAL COMBUSTION ENGINES

Youston Sekella, Elmira, N. Y., assignor to Eclipse Machine Company, Elmira, N. Y., a corporation of New York

Application June 21, 1935, Serial No. 27,754

9 Claims.

(Cl. 74—7)

The present invention relates to a starter drive for internal combustion engines of the type which automatically engages and drives a member of the engine to be started, and more particularly to a yielding connection incorporated in such drive.

It is an object of the present invention to provide a novel starter drive which is small and compact although powerful and efficient in operation.

It is another object to provide such a device which is balanced both statically and dynamically and retains such balance during use.

It is a further object to provide such a device which incorporates a yielding driving connection in the form of a spring with novel connecting and supporting structure therefor.

It is another object to provide such a device which is arranged to enclose and compress the spring prior to the application of torque thereto.

It is another object to provide such a device in which the convolutions of the spring are radially flattened and may be caused to engage frictionally for the transmission of torque.

Further objects and advantages will be apparent from the following description taken in connection with the accompanying drawing in which:

Fig. 1 is a side view partly in section of a preferred embodiment of the invention;

Fig. 2 is a detail in side elevation showing the attachment of the spring;

Fig. 3 is an extended view of certain of the parts of the drive, including the yielding driving connection, showing the parts disassembled but in their proper relative positions; and

Fig. 4 is a vertical section taken substantially on the line 4—4 of Fig. 1.

Referring first to Fig. 1 of the drawing, there is illustrated a power shaft 1 which may be the extended armature shaft of a starting motor, not shown, said shaft being journaled at 2 adjacent a member such as a flywheel gear 3 of an engine to be started. A sleeve 4 is rigidly mounted on the power shaft 1 by suitable means such as a key 5 (Fig. 4), and a locating pin or screw 6, one end of said sleeve being enlarged to form a driving head 7 which is provided with flattened surfaces 8 and 9 for a portion of its length leaving shoulders 11 and 12 adjacent the end thereof.

A hollow screw shaft 13 is freely journaled on the sleeve 4 and a nut 14 is threaded thereon and connected by a barrel 15 to an engine driving member in the form of a pinion 16 freely jour-

nalled on the power shaft 1 in position to be moved longitudinally into and out of mesh with the engine flywheel gear 3. An abutment in the form of a stop nut 17 is rigidly fixed on the inner end of the sleeve 4 and limits the longitudinal movement of the screw shaft 13 and nut 14 in the direction toward the engine member, an anti-friction washer 18 being preferably mounted on the sleeve adjacent the stop nut 17.

The threads on the shaft 13 are preferably cut away to form a smooth portion 19 at the idle position of the nut 14 whereby when the pinion 16 is demeshed, the nut may run off the ends of said threads, the pinion, barrel and nut being thus permitted to rotate freely until their momentum is dissipated. A spring 21 is provided in the barrel between the pinion and stop nut 17 in order to insure initial engagement of the nut 14 with the threads on the shaft 13. A light spring 22 is also provided between the abutment 17 and nut 14 for yieldingly preventing drifting of the pinion toward the engine gear.

According to the present invention, a yielding driving connection is provided between the driving head 7 on the sleeve 4 and a similarly formed driven head 23 on the screw shaft 13 in the form of a torsion spring 24 having spaced radially flattened convolutions terminating in outwardly turned hooks 25 and 26 (Fig. 3). Supporting and anchoring members in the form of discs 27 and 28 are slidably and non-rotatably mounted on the driving and driven heads respectively, rotation of the discs on the heads being prevented by engagement of the flat walls 29 and 31 of the openings in the discs with the corresponding flat surfaces 8 and 9 of said heads. The discs are provided with notches 32 and 33 extending radially inward from their peripheries and having rounded shoulders as best seen at 34 in Fig. 2 conforming to the shape of the hooks 25 and 26 and forming an anchorage therefor. Said discs are preferably formed on their opposed sides with helical surfaces of substantially the same pitch as the spring, thus forming seats for the end convolutions thereof as clearly illustrated in Fig. 2. The end convolutions of the spring are preferably wound down to conform to the surfaces of the driving and driven heads in order to make the anchorage rigid and hold the spring concentric.

Suitable thrust and friction washers are interposed between the driving head 7 and driven head 23, and here take the form of a pair of metal washers 35 and 36, with a fiber washer 37 interposed therebetween.

The locating pin 6 is preferably positioned in the driving head 4 beneath the normal position of the anchoring disc 27 whereby accidental loosening of the pin is effectively prevented. Removal thereof is, however, readily accomplished by moving the disc 27 toward the driven head against the compression of the spring 24 until the head of the pin is exposed.

In the operation of this device, rotation of the power shaft 1 by the starting motor causes the sleeve 4 to rotate and carry with it the anchoring disc 27. This rotation is transmitted through the spring 24 to the disc 28 on the screw shaft 13 which is thus caused to rotate and thereby translate the nut 14 threaded thereon with the barrel 15 and pinion 16 to mesh the pinion with the engine gear 3. When the meshing action is completed, the nut 14 engages the thrust washer 18 of abutment 17 whereby further translation of the nut is prevented. The screw shaft 13 is then forced back, compressing the spring 24 until the driven head 23 engages the thrust washer 35. Cranking torque is thereupon transmitted to the screw shaft through the frictional driving action of the washers 35, 36, 37 and through the torsional windup of the spring 24. It will be understood that since the spring is compressed substantially solid before the cranking load is assumed thereby, escape of the hooks 26 from the slots 32, 33 of the anchoring discs is effectively prevented.

It is within the purview of the invention to omit the thrust washers 35, 36 and 37 and allow the end thrust of the screw shaft 13 to be taken entirely by the spring 24 whereby the convolutions thereof are pressed together and transmit cranking torque frictionally. It has been found, however, that the frictional transmission of torque is more easily controlled by means of the thrust washers.

When the engine starts, the overrunning of the engine flywheel 3 accelerates the pinion and its connected parts, causing the nut 14 to overrun the screw shaft and return to its idle position, thus permitting the screw shaft to return to its normal position under the expansive effect of the spring 24.

It will be understood that various changes may be made in the design and arrangement of the parts of this device without departing from the spirit of the invention as defined in the claims appended hereto.

What is claimed is:

1. In a starter drive a power shaft, a pinion freely journalled thereon for longitudinal movement into and out of engagement with a member of an engine to be started, a screw shaft rotatably mounted on the power shaft, a nut threaded on said screw shaft and rigidly connected to the pinion, a stop member fixed on the power shaft defining the normal position of the screw shaft and the operative position of the nut, and means for rotating the screw shaft from the power shaft including a torsion spring and a pair of anchoring and supporting members non-rotatably connected to the power shaft and screw shaft respectively, having recesses and helically inclined seats, the terminal convolutions of said spring conforming to said seats and having outwardly turned ends engaging in said recesses, said screw shaft being free to slide on the power shaft away from said stop responsive to the longitudinal component of the driving forces transmitted through the screw and nut, thus compressing the

spring between the anchoring and supporting members.

2. In a starter drive a power shaft, a pinion freely journalled thereon for longitudinal movement into and out of engagement with a member of an engine to be started, a screw shaft slidably and rotatably mounted on the power shaft, a nut threaded on said screw shaft and rigidly connected to the pinion, an abutment for said nut fixed on said power shaft between the screw shaft and pinion, and means for rotating the screw shaft from the power shaft including a torsion spring and a pair of anchoring and supporting members non-rotatably connected to the power shaft and screw shaft respectively, having recesses and helically inclined seats, the terminal convolutions of said spring conforming to said seats and having outwardly turned ends engaging in said recesses, said nut being arranged to move longitudinally to mesh the pinion with the engine member upon rotation of the screw shaft, engagement of the nut against the abutment causing the screw shaft to move backward and compress the spring, preventing escape of the outwardly turned ends of the spring from the recesses in the anchoring and supporting members.

3. In a starter drive a power shaft, a member adapted to engage and drive a member of an engine to be started, and a driving connection therebetween including a torsion spring having radially flattened normally spaced convolutions and longitudinally outwardly turned ends, anchoring and supporting members connected respectively to the power shaft and engine driving member and having helical seals to receive and support the terminal convolutions of the spring, and recesses to receive the outwardly turned ends of the spring, said driving connection also including means for compressing the spring between the anchoring and supporting members concomitantly with the application of torque thereto, whereby the ends of the spring are prevented from slipping out of said recesses and the convolutions of the spring are uniformly compressed while being prevented from weaving or tipping over.

4. In a starter drive a torsion spring having radially flattened normally spaced convolutions, anchoring discs for the spring having helical surfaces forming seats for substantially the entire end convolutions thereof, and means forcing the discs together to compress the spring therebetween prior to the application of cranking torque thereto.

5. In a starter drive a torsion spring having radially flattened normally spaced convolutions terminating in longitudinally extending hooks, a pair of anchoring discs for the spring having recesses for receiving said hooks and helical surfaces conforming to the end convolutions of the spring, and means for compressing the spring between said discs concomitantly with the transmission of torque therethrough during the cranking operation.

6. In a starter drive a torsion spring having radially flattened normally spaced convolutions terminating in substantially quadrantal longitudinally extending hooks, a pair of anchoring discs for the spring having helical surfaces forming seats for the end convolutions thereof and peripheral recesses for receiving said hooks, the driving sides of said recesses being defined by curved shoulders conforming to the curvature of the hooks, and means responsive to cranking

torque transmitted therethrough for compressing said spring between the discs.

7. In a starter drive for internal combustion engines a power shaft, a pinion journalled thereon for longitudinal movement into and out of engagement with a member of an engine to be started, means for actuating the pinion from the shaft including a torsion spring, a driving head, an anchoring member for the spring non-rotatably mounted on the driving head, and means for locating the driving head on the shaft, said anchoring member being arranged to normally surround and retain said locating means.

10 8. In a starter drive for internal combustion engines a power shaft, a pinion journalled thereon for longitudinal movement into and out of engagement with a member of an engine to be started, means for actuating the pinion from the shaft including a compressible torsion spring, a driving head, an anchoring member for the spring

non-rotatably mounted on the driving head, and means for locating the driving head on the shaft, said anchoring member being arranged to normally surround and retain said locating means, and being movable along the shaft against the compression of the spring to free the locating means.

5 9. In a starter drive for internal combustion engines a power shaft, a pinion journalled thereon for longitudinal movement into and out of engagement with a member of an engine to be started, means for actuating the pinion from the shaft including a torsion spring, a driving head, an anchoring disc member for the spring non-rotatably mounted on the driving head, and a 10 locating pin traversing the driving head and entering the shaft, said anchoring disc being yieldably held by the longitudinal pressure of the spring in position to cover and retain said pin.
